UNITED STATES PATENT OFFICE.

WILLIAM L. BESSOLO, OF CLEARWATER, CALIFORNIA.

PIPE WRENCH.

Application filed July 9, 1923. Serial No. 650,273.

This invention relates to a wrench for pipes, tubings, etc., and it is an object of the invention to provide an effective, convenient and reliable tool of this character.

5 It is a general object of this invention to provide an improved, effective and convenient means for releasably setting a wrench of the chain type in operating position on a pipe or the like.

10 It is another object of this invention to provide a wrench which will effectively engage and grip completely around a pipe or the like, so that it will not slip and will not injure the pipe.

15 The various objects and features of my invention will be best and more fully understood from the following detailed description of a typical preferred form of the invention, throughout which description reference is had to the accompanying drawings, in which:

Fig. 1 is a view showing my improved wrench arranged on a pipe ready to be set in operating position;

25 Fig. 2 is a view similar to Fig. 1, showing one of the side plates in section, and showing the tool set in operating position on the pipe;

Fig. 3 is an enlarged detail sectional view, 30 taken as indicated by the line 3—3 on Fig. 2;

Fig. 4 is a central section view of the wrench, showing it set ready for operation;

Fig. 5 is an enlarged detail sectional view, taken as indicated by the line 5—5 on 35 Fig. 1;

Fig. 6 is an enlarged detail sectional view, taken as indicated by the line 6—6 on Fig. 1;

Fig. 7 is an enlarged side elevation of a 40 portion of the handle, showing the safety catch in operation; and

Fig. 8 is a detailed transverse sectional view, taken as indicated by the line 8—8 on Fig. 7.

45 The wrench provided by this invention includes, generally, a lever 10, a flexible jaw 11, means 12 permanently connecting the inner end of the flexible jaw 11 with the lever 10, means 13 for releasably operatively connecting the outer end of the flexible jaw 11 with the lever 10, and means 14 operable to set the means 13.

The lever 10, in its preferred form, includes a handle 15, and a head 16 at the 55 inner end of the handle. The head 16 is preferably flat and in the form of an en-

largement at the inner end of the handle 15.

The flexible jaw 11 may be in the form of a chain, including links 17, connected by pintle pins 18. The present invention is, 60 of course, not concerned with the details of the form or construction of the flexible jaw 11, it being important only for it to have the desired gripping action and that it be sufficiently flexible to operate as hereinafter 65 described. It is desirable to design and construct the jaw 11 so that it will conform closely to a pipe or the like, and that it be strong and durable. The inner side of the chain may be roughened, or otherwise 70 constructed, so that it is effective in gripping a pipe or the like.

The means 12, which connects the inner 75 end of the flexible jaw 11 with the head 16, includes two cheek or side plates 19 arranged at opposite sides of the head 16 and provided with parts 20 which project from the head. The plates 19 are connected to the head by a pivot pin 22. The links 17, at the inner end of the flexible jaw 11, are 80 arranged between the parts 20 and are connected with the parts 20 by a pivot pin 21.

The means 13, for connecting the outer 85 end of the flexible jaw 11 with the head 16, includes an arcuate-toothed jaw 23 connected to the outer end of the chain by a pivot pin 24, a series of teeth 25 provided on the outer part of the head 16 to cooperate with the teeth of the jaw 23, and means for operating the head 16 to put the teeth 25 into cooperative engagement with the teeth of the 90 jaw. The jaw 23, which is practically a part or continuation of the flexible jaw 11, is preferably rigid, and is adapted to extend between the side plates 19 and between the 95 head 16 and pipe "P", in the manner illustrated in Figs. 1, 2, and 3, of the drawings. The teeth 26, at the outer edge of the jaw 23, have faces 27 which face inwardly or toward the flexible jaw 11. The teeth 25 on the outer part of the head 16 have faces 28 adapted to cooperatively engage the faces 27 of the teeth 26.

The means 14 provided by my present invention for putting the teeth 25 and 26 into cooperative engagement, includes, generally, cam means at or in combination with the connection between the head and the side plates operable to shift the head relative to the side plates, and means for releasably locking the cam means in its actuated position. 110 In the particular form of the invention

illustrated in the drawings the means 14 includes a cam 30 mounted on the pin 22 to operate in an opening 31 in the head 16, and an operating handle 32 in connection with the pin 22 whereby the pin can be rotated to actuate the cam. The cam shown in the drawings is in the form of a round disk mounted eccentrically on the pin 22, while the opening 31 in the head is also round and 10 rotatably carries the cam 30. The cam may be secured or fixed on the pin 22 by a suitable key 34 or the like. The cam 30 is mounted and proportioned so that it moves or shifts the head 16 with relation to the 15 plates 19 the desired amount and in the desired directions. When the cam is operated, as I hereinafter describe, the head moves toward the jaw 23 so that the teeth 25 are moved into engagement with and toward the 20 faces of the teeth 26. The operating handle 32 may be in the form of a small lever mounted on one end of the pin 22 at the outer side of one of the side plates 19. The handle may be secured or fixed on the pin 22 25 by a suitable key 35, or the like. It is preferred to mount the handle 32 on the pin 22 so that it extends at substantially right angles to the handle 15 when the head is in its out or released position and is substantially 30 parallel with the handle 15 when the head is in its operating or in position. The cam and handle are related so that the handle is swung in the direction indicated by the arrow "A" in Fig. 1, to cause actuation of the 35 head from the released position to the operating position.

For the purpose of locking the head in operative position a latch 40 is pivotally mounted on the cam operating handle 32 to cooperate with the handle 15. The latch 40 is arranged at the outer end of the handle 32 and is carried by a pivot pin 41. The main part of the latch extends inwardly under the handle 32 and has a downwardly projecting part 42 adapted to extend into a recess 43 in the upper side of the handle 15. A spring 44 is arranged between the handle 32 and the latch to normally yieldingly hold the latch down and shoulders 45 are provided on the latch and handle so that they cooperate to limit the downward movement of the latch. A handle 46 is provided on the latch so that it projects from the end of the handle 32 and is in position so that it can be conveniently depressed when the handle 32 is gripped. The handle 15 has an inclined surface 47 at the recess 43 to lift the latch as the handle 32 is being moved to position where the part 42 will drop into the recess 43.

A gripping plate 50 is provided at the projecting parts of the side plates so that the tool will grip as effectively at that point as at other points. The plate 50 extends between the projecting parts 20 of the side

plates, its ends being carried in recesses 51 in the projecting parts. In the form of the invention illustrated in the drawings the plate 50 is connected with the other parts of the tool by a lug 53 provided on the plate 70 so that it extends between the links 17 at the inner end of the flexible jaw and is held by the pivot pin 21. The face of the plate may be provided with teeth 55, or the like, so that it is effective in gripping a pipe, or the like. In practice I prefer to make the plate 50 as large as possible without interfering with the other parts. By providing the plate 50 the tool will grip practically uniformly around a pipe and will have as much bearing or gripping surface at the projecting parts of the side plates as at any other point.

In applying the tool to a piece of work, for instance, a pipe "P", the flexible jaw 11 is arranged around the pipe and the jaw 23 is arranged between the side plates 19 and the head 16 and pipe "P" as far as it will go. During the time that the jaw 23 is being arranged in place the handle 32 is in the position shown in Fig. 1 so that the head 16 is in its released position. To throw or set the tool in operating condition the handle 32 is swung in the direction indicated by the arrow "A" so that the side plates 19 and head 16 move relatively until the head is in its in position with the teeth 25 at the outer part of the head 16 in cooperative engagement with the teeth 26 on the jaw 23, as illustrated in Fig. 2 of the drawings. Upon the parts reaching this position the part 42 of the latch enters the recess 43 to automatically catch and lock the tool in the set position. To operate the tool the handle 15 is swung in the direction indicated by the arrow "B" in Fig. 1, so that the head 16 swings or turns, causing the jaw 23 to be moved or urged in the direction indicated by the arrow "C" in Fig. 1, thereby causing the flexible jaw 11 to tightly grip the pipe "P". Further movement of the lever will cause operation or turning of the pipe "P". When it is desired to release the tool from the pipe the latch is released by depressing the handle 46 and the handle 32 is swung back to the position shown in Fig. 1, thus causing the teeth 25 to withdraw from the teeth 26 allowing the jaw 23 to be withdrawn and the jaw 11 opened. From the foregoing description of the construction and scheme of operation of my improved wrench it will be obvious that it is extremely simple, effective and reliable in operation, that it will operate effectively on work of various sizes, and that it is simple, practical and comparatively inexpensive of construction.

Having described only a typical preferred form of my invention I do not wish to limit myself to the specific details hereinabove set forth but wish to reserve to myself any 130

changes or variations that may appear to those skilled in the art or fall within the scope of the following claims.

Having described my invention, I claim:

5. 1. A wrench including, a lever, a flexible jaw adapted to be arranged around an object, one end of the jaw being adapted to be arranged between the lever and object, and cam means connecting the other end of the 10 jaw with the lever operable to shift the lever relative to said first mentioned end of the jaw, the cam means having sufficient throw to move the lever into and out of cooperative engagement with the first mentioned 15 end of the jaw.

2. A wrench including, a lever, a flexible jaw adapted to be arranged around an object, one end of the jaw being adapted to be arranged between the lever and object, a 20 shiftable pivotal connection between the other end of the jaw and the lever whereby the lever is shiftable relative to said first mentioned end of the jaw, the cam means having sufficient throw to move the lever 25 into and out of cooperative engagement with the first mentioned end of the jaw, and operating means for the connection.

3. A wrench including, a lever, a flexible jaw adapted to be arranged around an object, a shiftable connection between one end 30 of the jaw and the lever whereby the lever is shiftable relative to said end of the jaw to move into and out of cooperative engagement with the other end of the jaw, and releasable means for automatically locking the lever 35 in position to cooperate with said other end of the jaw upon its being moved thereto.

4. A wrench including, a flexible jaw adapted to be arranged around an object, a 40 plurality of teeth at the outer end of the jaw, a lever having a part adapted to cooperatively engage the teeth, and single means connecting the inner end of the jaw with the lever so that it can swing relative to the lever and so that the lever is shiftable relative to it to move said part into and out of cooperative engagement with the teeth.

5. A wrench including, a flexible element, a jaw at the outer end of the flexible element, 50 teeth on the jaw, a lever having teeth at its inner end, and means pivotally shiftable connecting the inner end of the flexible element with the lever so that the lever is shiftable relative to the inner end of the element to move the teeth on the lever into and out of cooperative engagement with the teeth of the jaw.

6. A wrench including, a lever having 60 teeth at its inner end, a chain adapted to be arranged around an object, a plate connecting the inner end of the chain with the lever, a toothed jaw at the outer end of the chain

adapted to extend between the object and the inner end of the lever, means at the connection between the plate and lever operable 65 to move the lever relative to the plate so that the teeth on the lever cooperatively engage the teeth on the jaw, and an operating lever attached to said means.

7. A wrench including, a lever having 70 teeth at its inner end, a chain adapted to be arranged around an object, a plate connecting the inner end of the chain with the lever, a toothed jaw at the outer end of the chain adapted to extend between the object and the 75 inner end of the lever, means at the connection between the plate and lever operable to move the lever relative to the plate so that the teeth on the lever cooperatively engage the teeth on the jaw, an operating lever for 80 said means, and a manually releasable catch in connection with the operating lever operable to automatically lock the operating lever in position with the teeth in cooperative engagement.

8. A wrench including, a lever, a flexible jaw adapted to be arranged around an object, a connection between one end of the jaw and the lever whereby the lever is shiftable relative to said end of the jaw into cooperative engagement with the other end of the jaw, an operating handle operable to shift the lever, and means for automatically locking the lever in position to cooperate with said other end of the jaw upon its being 95 moved thereto including, a spring latch connected with the handle to cooperate with the lever to prevent movement of the handle.

9. A wrench including a flexible jaw, two parts, one a lever adapted to cooperatively engage the outer end of the jaw the other a plate connected with the inner end of the jaw, a pin extending through the lever and plate to connect them, a cam on the pin cooperatively engaging one of the parts to cause shifting of the parts upon rotation of the pin, and an operating lever on the pin.

10. A wrench including, a flexible jaw, a lever having an opening through it at its inner end, a plate connected with the inner end of the jaw, a part at the inner end of the lever adapted to cooperatively engage the outer end of the jaw, a pin extending through the plate and lever to connect them, a cam on the pin and arranged in said opening so that it causes shifting of the lever relative to the plate when the pin is rotated, and an operating handle for the pin.

In witness that I claim the foregoing I have hereunto subscribed my name this 29th day of June, 1923.

WILLIAM L. BESSOLO.
